APPARATUS FOR REFINING OIL

Original application filed January 14, 1925, Serial No. 2,262. Divided and this application filed December 15, 1928. Serial No. 326,218.

This invention relates to improvements in apparatus for the distillation and refining of lubricating oils. The invention provides an improved apparatus for producing lubricating oils from oils and distillates containing lubricating oil fractions, such as crude petroleum oil, topped crude oil, and crude lubricating oil distillates. This application is a division of an application filed January 14, 1925, Serial No. 2,262.

Hitherto, in the art of producing lubricating oils from crude oil, the crude oil has been initially subjected to a fractional distillation, either by batch operations or in a series of continuous stills, and a broad lubricating oil distillate fraction thereby separated from the crude oil; and this lubricating oil fraction has then been subjected to redistillation in the presence of caustic alkali introduced directly into the body of oil undergoing distillation for the production of refined lubricating oil distillates, the caustic alkali solution being employed to remove undesirable constituents such as naphthenic acids and asphaltic compounds which if allowed to distill over with the finished lubricating oil distillates would render them bad colored and difficult to handle in further treatment. It has been proposed to apply the caustic alkali treatment directly to the crude oil undergoing distillation during the time in which the broad lubricating oil fraction was being produced, but such proposals have not been successful principally because of excessive deposition within the still due to the accumulation of caustic alkali in the residuum and to the combined effect of such caustic alkali and impurities normally present in the crude oil.

The apparatus of the present invention, as applied to the production of lubricating oils, provides for vaporization of the lubricating oil fractions from the crude lubricating oil-containing oil or distillate, treatment of the vaporized lubricating oil constituents with a caustic alkali, and recovery of the treated lubricating oil constituents.

In applying the apparatus of the present invention to the production of lubricating oil, the vaporized lubricating oil constituents are subjected to treatment with caustic alkali

while primarily in the vapor phase, and any condensate formed in the treating operation is also subjected to treatment in the liquid phase. The alkali treatment of the lubricating oil fraction or fractions is thus effected before or as the lubricating oil constituents are condensed and in this way redistillation for treatment of the lubricating oils with caustic alkali can be eliminated. Moreover, the refining operation, when carried out in this way, has several other important advantages. Thorough and intimate contact between the caustic alkali and the lubricating oil can be effected and the refining action advantageously promoted. Likewise, the entire lubricating oil distillate fraction is positively subjected to thorough treatment with the caustic alkali; in the ordinary distillation with alkali the initially distilled components may escape without thorough contact with the alkali. The caustic alkali treatment also may be combined advantageously with fractionating operation for separation of the desired lubricating oil fractions. The elimination of a distilling operation, particularly the crude distillation as ordinarily carried out, also assists in eliminating cracked products from the finished lubricating oil products. Cracked constituents are usually characterized by low viscosity as compared to their boiling point and are accordingly usually objectionable in lubricating oils of corresponding boiling range. Other advantages of the invention will be apparent from the following description.

In the operation of the apparatus of the present invention, the lubricating oil fraction may be vaporized from the crude oil or crude lubricating oil distillate in a vaporizing still and this vaporization may be effected under atmospheric pressure or it may be effected under a subatmospheric pressure. The vaporization may be carried out with or without the introduction of steam or an inert gas. One advantageous way to carry out the vaporization is with the introduction of steam and under reduced pressure. After vaporization, the vaporized lubricating oil constituents may be subjected to a fractionating operation, for example, by passing the vapors

from the vaporizing still through a fractionating tower, or the operation of the vaporizing still may be controlled so that only the desired vapors of the desired lubricating oil fraction are produced. Where a fractionating tower is employed, it may be externally cooled or it may be cooled by introduction of a refluxing agent such as a portion of the distillate produced in the operation; and the fractionating tower may be arranged to discharge reflux back into the still or the heavier constituents separated in the tower may be removed from the tower without being returned to the still. Where a fractionating tower is employed in connection with the vaporizing still, the crude oil or crude lubricating oil distillate may be introduced into the tower and employed as a refluxing agent therein; and the operation of the tower and vaporizing still may be controlled so that vaporization of the desired lubricating oil fraction from the crude material introduced into the tower is substantially completed in the tower.

From the vaporizing still, or from the fractionating tower connected with the vaporizing still, the vaporized lubricating oil constituents are conducted to a treating tower in which they are subjected to treatment with caustic alkali. In the treating tower, the lubricating oil vapors are thoroughly and intimately contacted with a caustic alkali solution. The treating tower may be of conventional baffle tower construction arranged for introduction of the vapors into the lower part of the tower and of the treating solution into the upper part of the tower so that the lubricating oil vapors are contacted in counter current flow with the caustic alkali solution. In the treating tower, a part of the oil vapors are condensed and the condensate mingle with the used treating solution.

The caustic alkali solution employed may, for example, be an aqueous solution of sodium hydroxide of a density of between about 10° and 20° Bé. The minimum amount of caustic alkali solution employed should be at least sufficient to remove the undesirable constituents from the lubricating oil vapors being treated, but the maximum amount employed may vary widely as will appear hereinafter. For example, the rate of introduction into the treating tower of the sodium hydroxide solutions just referred to may vary from 1/2% to 15% or more on the weight of vapors entering the treating tower. An excess of the caustic alkali solution, over that required to effect the desired refining operation, does not injure the quality of the lubricating oil distillate fractions produced, but such an excess of treating solution may produce an increased cooling effect in the tower with the condensation of an increased proportion of the vapors therein. Condensation within the treating tower may be regulated by controlling

the amount of treating solution introduced therein. Where an aqueous solution of caustic alkali is employed in the treating tower, part of the water may be evaporated from the solution in the tower with resulting increase in concentration of caustic alkali in the solution, and the condensate mixture, including the used caustic alkali solution and any condensate produced in the treating tower, which accumulates may comprise a suspension of caustic alkali in oil in admixture with a more or less concentrated solution of caustic alkali.

By appropriately regulating the cooling effected in the treating tower, for example by controlling the amount of treating solution circulated through the tower, a lubricating oil distillate fraction may be separated from the vapors in the treating tower. A lubricating oil fraction may similarly be separated in the treating tower by externally cooling the tower. After discharge from the treating tower, the condensate mixture may be cooled and the lubricating oil fraction separated from the used caustic alkali solution, for example by decantation after allowing the caustic alkali solution to settle. In this way, a refined lubricating oil fraction, free from the lighter vapors which escape through the treating tower. In such an operation, additional caustic alkali is employed with advantage for promoting the condensation in the treating tower since the excess of caustic alkali solution facilitates the separation of the used caustic alkali solution from the condensed lubricating oil fraction. By carrying out the operation in this manner, in conjunction with a vaporizing still having a fractionating tower thereon, a closely controlled fraction can be separated in the treating tower, heavier constituents being removed from the vapors in the fractionating tower and lighter constituents escaping through the treating tower uncondensed.

The operation of the treating tower may also be regulated so that the main portion of the vaporized lubricating oil constituents pass therethrough without being condensed therein. For carrying out the operation in this way, the treating tower may be thoroughly lagged to prevent heat loss and the treating solution may be preheated before introduction into the treating tower. In this manner, the treating tower operation can be controlled so that only heavier constituents are condensed therein and so that only a minimum proportion of such heavier constituents are condensed. Any lubricating oil constituents condensed in the treating tower may be separated from the tower condensate mixture and recovered.

The uncondensed vapors escaping from the treating tower are condensed, for example in an ordinary water cooled condenser. Where the main portion of the lubricating oil frac-

tion is separated in the treating tower, the condensate from the vapors escaping from the treating tower comprises the lighter constituents uncondensed in the treating tower.

5 Where the treating tower is operated to condense a minimum proportion of the lubricating oil fraction, the condensate from the vapors escaping from the treating tower comprises the lubricating oil distillate fraction.

0 Where the vaporized constituents escaping from the still, or from the fractionating tower on the still, include constituents lighter than those desired in the lubricating oil fraction, this final condensate also includes such

5 lighter constituents and may be subjected to further treatment for the separation of these lighter constituents therefrom. The vaporizing operation and the initial fractionating operation, however, may be controlled so that 0 the final condensate produced from the vapors escaping from the treating tower is the desired lubricating oil distillate fraction.

Before the vapors escaping from the treating tower are condensed, they may be subjected to a further fractionating operation. They may, for example, be passed through a second fractionating tower in which the desired lubricating oil fractions are condensed and through which the constituents lighter 0 than those desired in the lubricating oil fractions are allowed to pass uncondensed. Such a second fractionating tower may be employed in conjunction with the treating tower for the production of a closely controlled lubricating oil distillate fraction by regulating the operation of the treating tower to condense heavier constituents and by regulating the operation of the second fractionating tower to permit lighter constituents to escape uncondensed therethrough. Where such a second fractionating tower is employed, a heavier lubricating oil fraction may be separated in the treating tower and a lighter lubricating oil fraction, which tower is free from the 5 lightest undesirable constituents, can be separated in the fractionating tower.

The apparatus of the present invention consists of a series of continuously operating vaporizing stills in which a series of progressively heavier fractions are treated for the separation of progressively heavier distillates, or through which the crude oil or crude lubricating oil distillate is successively passed with vaporization therefrom of progressively 5 heavier fractions in successive stills of the series. The oil component of the condensate mixture separated in towers operating on lighter vapors is introduced into treating towers operating on heavier vapors with improvement of the fractionation effected in the several distillation stages. The caustic alkali associated with the oil in the condensate mixture from preceding treating towers may be introduced with the oil into successive 0 treating towers and employed for treatment

of the heavier vapors therein, or the caustic alkali component of the condensate mixture may be separated and fresh alkali supplied to successive treating towers.

The invention will be further described in connection with the accompanying drawing which illustrates in a diagrammatic and conventional way, one form of the apparatus of the invention; but it will be understood that this further description and illustration are intended for the purpose of exemplifications and that the invention is not limited thereto.

The apparatus illustrated is arranged for continuous operation with separation of a plurality of cuts or fractions in each of a series of stills, and comprises a series of stills, fractionating towers, treating towers and condensers. While the apparatus illustrated comprises three stills, it will be apparent that a greater or lesser number could be employed 5 for the separation of a greater or lesser number of fractions. In the three stills shown, the same parts are designated by the same reference numeral, with *c* appended in the second still 5^c, and with *d* appended in the 0 third still 5^d.

The apparatus for the separation of the first cut or fraction comprises a vaporizing still 5, a fractionating tower 6, a treating tower 7, and a cooler and condenser 8. The still illustrated is of the direct fire heated type. The still is provided with a charging line 11 and a residue draw-off 12. The fractionating tower 6 is arranged above the still. This tower is provided with a helical baffle 13 and the vapors from the still pass upwardly through the helical passage in the tower escaping from the upper end of the tower through the vapor line 14. Connection 15 is arranged near the upper end of the tower for the introduction of charging stock into the still through the tower.

From the vapor line 14 the vapors enter the treating tower 7, the tower shown being of conventional baffle construction, and pass upwardly therethrough about the baffles 17 arranged in the tower. A pump 18 is arranged to force caustic alkali solution into the upper end of the treating tower through connection 19 and the spray head 20 arranged in the upper end of the tower. The vapors rising through the treating tower escape through the vapor line 21 to the condensing coil 22 from which condensate is discharged, into conventional look-boxes and receivers. The treating solution is supplied to the pump 18 through connection 31, which communicates with tank 32 through connection 33 having valve 34 therein. The condensate mixture collecting in the lower part of the treating tower 7 is discharged through connection 38 to the tank 35. A separation of condensate and treating solution may be effected in the tank 35. The oil condensate is lighter than the admixed caustic alkali solu- 130

tion and tends to float thereon; and connection 46 is provided for withdrawing separated oil from the upper layer collecting in the tank and connection 47 for withdrawing used caustic solution from the lower layer. A separation may thus be effected in the tank 35 between the oil and the used caustic solution of the condensate mixture, and as much of the used caustic solution as may be desired may be employed in the next treating tower together with fresh caustic solution from the tank 76.

The exposed parts of the still 5 and the fractionating tower 6 and the vapor line 14 are advantageously heat insulated or lagged to prevent unnecessary heat loss. Where it is desired to pass the maximum amount of vapor through the treating tower 7 unden-
15 sired, the treating tower is also advan-
tageously lagged or heat insulated. Where, however, it is desired to separate a fraction from the vapors in the treating tower the treating tower may be exposed to the atmosphere for cooling to effect condensation of the
20 desired fraction.

Where the apparatus illustrated is em-
ployed for vacuum distillation, the still 5 and the fractionating tower 6 and the treat-
ing tower 7 are suitably constructed and rein-
forced to prevent collapse under the excess
of atmospheric pressure prevailing on the
outside over the reduced pressure within the
distilling apparatus, and suitable precautions
are taken to prevent inleakage of air. The
35 several vapor connections and the passages
through the fractionating towers and treat-
ing tower are also made of sufficient cross-
sectional area so that the desired degree of
vacuum can be maintained without excessive
40 consumption of power. For maintenance of
subatmospheric pressures within the distill-
ing system, a vacuum pump is arranged be-
yond the receiver and look-box and suitable
valves and pumps are arranged where needed
45 for pumping liquid against the vacuum.

A connection 70 including a pump 71 is provided for withdrawing residual oil from the still 5 and introducing it into the tower 6^c on the still 5^c, and a connection 72 including
50 a pump 73 is provided for withdrawing residual oil from the still 5^c and introducing it into the tower 6^a on the still 5^a. A connection 74 is provided for supplying the treating solu-
tion to the treating tower 7^c through the
55 pump 18^c and the connection 19^c, and a connection 75 is provided for supplying the treating solution to the treating tower 7^a. The connection 74 is arranged to withdraw
fresh caustic alkali solution from tank 76
60 through connection 77 and to withdraw from
the tank 35 either condensate mixture
through connection 33 or the separated oil
component of the mixture through connec-
tion 46. The connection 75 is arranged to
65 withdraw fresh caustic alkali solution from

tank 76^c through connection 36^c and to withdraw from the tank 35^c either condensate mixture through connection 33^c or the separated oil component of the mixture through connection 46^c.

In applying the apparatus to the production of lubricating oils, the still 5 is charged through the charging line 11 with oil or distillate containing the lubricating oil fractions. The still is heated and as vapors from the still rise through the fractionating tower 6 the feed of additional lubricating oil-containing charging stock is begun through connection 15. The distillation may be promoted by the introduction of live steam directly into the body of oil in the still. The supply of additional charging stock through connection 15 may be regulated to control the refluxing operation in the fractionating tower. The fractionating operation is regulated so that the desired lubricating oil constituents escape from the upper end of the fractionating tower 6 through the vapor line 14 and these lubricating oil vapors enter the treating tower 7. In the treating tower 7 the lubricating oil vapors are contacted in countercurrent flow with a caustic alkali solution supplied to the upper end of the tower through spray head 20 by means of the pump 18. This caustic alkali solution is fresh solution from the tank 32.

For the separation of a lubricating oil fraction in the treating tower, the circulation of treating solution through the tower is regulated to effect condensation therein of the desired lubricating oil constituents. The condensation effected by the treating solution, and by evaporation of water from the solution where an aqueous solution is employed, may be supplemented by external cooling of the treating tower. Where the condensate mixture or part of the condensate mixture is circulated through the next treating tower the condensate mixture may be cooled by circulation through the cooling coil 41 on its way to the tank 35. After separation from the used caustic solution in the tank 32, the lubricating oil fraction condensed in the treating tower 7 may be withdrawn through connection 46, and may be subjected to further settling or washing treatment or other suitable treatment for the separation of any remaining admixed caustic alkali.

For circulating the main portion of the lubricating oil vapors through the tower with a minimum of condensation therein, the treating tower is lagged and the circulation of treating solution through the tower is maintained at the minimum necessary to effect the desired refining operation. The treating solution entering the treating tower 7 through the spray-head 20 may be preheated. The lubricating oil vapors escape from the treating tower through the vapor line 21 and are condensed and collected. Where the operation is

carried out continuously in this manner, the condensate may include, in addition to the lubricating oil constituents, some lighter constituents which may be removed by further treatment. Any lubricating oil constituents 5 condensed in the treating tower collect in the tank 35 and may be withdrawn therefrom after separation from the caustic alkali solution therein.

0 The apparatus relates more particularly to operations in which fresh oil is supplied to the vaporizing still and residual oil withdrawn therefrom and in which a fraction of substantially uniform character is separated. 5 The apparatus of the present invention is also applicable where the distillation is carried out upon successive charges of oil with the successive separation of progressively heavier cuts either in the treating tower or 0 in the condenser or in both. The operation, for example, may be carried out by charging the still with oil and progressively distilling oil therefrom, permitting lighter constituents undesirable as lubricating oil constituents 5 to escape through the treating tower, beginning the introduction of caustic alkali solution into the treating tower as lubricating oil constituents begin to come over, and separating the distillate into the desired cuts. 0 The operation may be carried out under substantially atmospheric pressure. It will be understood, however, that if the pressure in the receiver is approximately equal to atmospheric pressure the pressure in the still 5 will be somewhat greater due to the resistance of flow of the vapors through the apparatus, but by suitably proportioning the cross sectional area of vapor passages through the apparatus to provide for free vapor flow this 0 resistance and the consequent increase in pressure may be made substantially negligible. The still itself may be operated at atmospheric pressure, or at much lower pressures, by maintaining a suitably reduced pressure 5 in the receiver. Where the operation is carried out as a batch operation upon successive charges of oil with separation of the distillate into progressively heavier cuts, reduced pressures may be employed with advantage 0 for eliminating light undesirable constituents from the lubricating oil fractions, and in carrying out the process of the invention the lubricating oil distillate can be separated into narrow fractions by regulating the operation 5 of the still, of the fractionating tower, and of the treating tower in accordance with the invention.

A series of progressively heavier charging stocks may be separately supplied to the several stills either through connections 15, 15^c and 15^d or through connections 11, 11^c, and 11^d the latter particularly where no fractionating tower is employed; or a lubricating oil-containing charging stock may with advantage 5 be supplied to the vaporizing still 5, after

vaporization of lighter components the heavier residual oil pumped to still 5^e, and after vaporization of another fraction in still 5^e the heavier residual oil pumped to still 5^d.

In the second treating tower the caustic alkali solution may include used alkali from the condensate mixture tank or fresh caustic alkali solution or a mixture of the two. In the apparatus illustrated, separate fresh alkali solution tanks are shown for each treating tower, but where only a single strength of treating solution is used only a single supply tank is necessary. More concentrated treating solutions may be used in the treatment of the heavier vapors; and, where the used alkali solution from the treatment of lighter vapors is employed in admixture with fresh alkali solution in the successive treatment of heavier vapors, the concentration of the composite alkali solution may be adjusted 70 by regulating the concentration of the fresh caustic solution admixed therewith. For example, water may be evaporated from the alkali solution in the treating tower and this more concentrated solution can be brought 75 to the proper degree of concentration for further use in a following treating tower by admixing a relatively dilute caustic alkali solution therewith. In successive treating 80 towers, treating solutions similar to those used in the second may be employed.

The oil component of the condensate mixture separated in the treating towers is introduced into a successive treating tower through which vapors heavier than those in the treating tower in which it is formed are 85 passing. The treating tower operation is controlled to separate heavier constituents, those heavier than desired in the particular cut, from the lubricating oil vapors passing therethrough, and these heavier constituents are introduced into a successive treating tower where heavier lubricating oil vapors are undergoing treatment. In the successive tower 90 the introduced oil is employed to promote separation of heavier constituents from the vapors therein in a similar way and the introduced oil is itself fractionated, the constituents corresponding to the desired cut being vaporized and escaping from the treating towers with the other vapors. The fractionation is thus improved. This is particularly advantageous where no fractionating 95 tower is employed between the vaporizing still and the treating tower.

The oil component of the condensate mixture may thus be separated from the admixed used alkali solution and employed in admixture with fresh alkali solution for introduction into a successive treating tower, or the condensate mixture itself, including the used alkali, may be directly introduced into a successive treating tower, either alone or with the addition of fresh alkali. The oil component of the treating tower condensate mix- 100 105 110 115 120 125 130

ture from the last still in the series may be subjected to further simple distillation, advantageously in the presence of an alkali, which alkali may be the used alkali component of the condensate mixture or fresh caustic alkali.

The apparatus of the invention is of general application to the production of lubricating oils from lubricating oil-containing oils and distillates. It may be applied to crude petroleums or to topped crude oils from which lighter constituents, such as gasoline, have been stripped. It is also applicable to the treatment of other oils and residues containing lubricating oil constituents, such as crude lubricating oil distillates and fractions. It may be employed in the treatment of oils of either asphaltic or paraffine base or mixed base oils. Following the distillation and refining treatment of the present invention, the lubricating oil distillate fractions may be filtered through fuller's earth or similar material or subjected to such other treatment as may be desired. Wax containing distillates, for example, may be subjected to suitable dewaxing operations in the usual manner. In referring to lubricating oils herein, reference is made to the petroleum oils characterized by oiliness and high viscosity. In general these oils may be defined as oils made up of constituents heavier than gas oil, having a gravity lower than about 35° Bé. and a viscosity upwards of about 50 at 100° F. Saybolt universal.

35 I claim:

An apparatus for the production of lubricating oils comprising a series of stills each provided with, a fractionating tower adapted to receive the vapors from the still, a treating tower connected to the fractionating tower and adapted to receive the vapors therefrom, a condenser connected to the treating tower and adapted to receive the vapors therefrom, and a cooler adapted to receive the condensate from the treating tower, means for supplying fresh caustic alkali to at least one treating tower of the series and means connected to the associated cooler for delivering at least a part of the condensate therefrom to 50 a succeeding treating tower of the series.

In testimony whereof I affix my signature.
GEORGE H. TABER, JR.
